UNITED STATES PATENT OFFICE.

JOHN C. EGLY, OF PHILADELPHIA, PENNSYLVANIA, ASSIGNOR TO
THOMAS A. PEARCE, OF SAME PLACE.

CIRCULAR-KNITTING MACHINE.

SPECIFICATION forming part of Letters Patent No. 357,472, dated February 8, 1887.

Application filed March 13, 1886. Serial No. 195,149. (No model.)

To all whom it may concern:

Be it known that I, JOHN C. EGLY, of Philadelphia, in the State of Pennsylvania, have invented certain new and useful Improvements in Circular-Knitting Machines, of which the following is a specification.

In the accompanying drawings, Figure 1 represents a central vertical section through the machine, showing the driving-shaft in elevation and the needle-cylinder in dotted lines. Fig. 2 is a sectional view of the needle-cylinder detached therefrom; Figs. 3 and 9, side and rear views, respectively, of the thread-carrier, the former showing certain parts in dotted lines and the latter representing part of the cam-cylinder in full lines; Figs. 4 and 5, plan and partial side views, respectively, of the ring which surrounds the needle-cylinder; Fig. 6, a front view of the needle; Fig. 7, a top or plan view of the machine, and Fig. 8 a top or plan view of a modification of the ring which supports the needle-cylinder.

In the drawings, A represents the support or frame of the machine; B, the driving-shaft, having a fast pulley, C, and loose one, C', with a belt-shifter, S, of any convenient form. The cam-cylinder E rests upon a ring, q, of the frame A, and is provided around its lower periphery with beveled teeth, which engage with the beveled gear D, mounted upon the shaft B.

A shield, U, incloses the proximate face of the beveled gear D, to prevent the work which descends through the cylinder from coming in contact with the gear. The cam-cylinder E is held down by the clamping-pieces P, arranged at suitable intervals above its horizontal flange y.

Within the ring q, which sustains the cam-cylinder, is a split ring, G, supported upon a bracket, H, which in turn is suspended by means of a vertical shaft, R, having a screw-thread around its upper end. This shaft R slides freely in a sleeve, A', which forms part of the frame A. The screw-thread upon shaft R engages with a similar thread upon a nut, h, which rests upon the top of the sleeve A'.

A collar, t, is clamped around the nut h by means of a tightening-screw, t', and said collar is provided with a spring-actuated stop-pin, I, whose lower end engages with one of the several openings i in the index-plate T. These

openings are numbered, as shown in Fig. 7, so that the operator may readily set the stop-pin in any desired hole, and for purposes of convenience I provide two movable pins, m, 55 which can be inserted in two holes, so as to limit the range of motion of the stop-pin in either direction, and thus save the necessity of consulting the numbers.

From the foregoing description it will be 60 seen that the ring G is suspended from the nut h, and that by turning said nut in either direction the screw-thread upon the vertical shaft R will cause said shaft, together with the bracket H and ring G, to rise or fall. 65

The needle-cylinder F rests upon a flange, g, of the ring G, and thus is raised or lowered by the rotation of the nut h. The ring G is split upon one side, as shown at a, and is provided upon a portion adjacent to said split 70 with a clamping-screw, j, whose milled head a' is shown in Fig. 7. When the needle-cylinder F is placed in position upon the flange g of the ring G, the screw j is turned so as to clamp the ring securely around the bottom of 75 the cylinder, and thus hold it firmly in position, no matter what may be the speed of the machine. To accommodate it to needle-cylinders of different diameters, I prefer to construct the ring G, as shown in Fig. 8, with projecting radial lugs M, arranged at convenient 80 intervals. Said lugs enable the operator to grip a small cylinder with firmness and obviate the necessity which would otherwise occur of making the ring G so thick that it would 85 not readily spring or yield to the screw j.

By providing a set of rings, each of which has the lugs M of a different height from the others, (as indicated on the right-hand side of Fig. 8, M') any size cylinder may be used; or 90 the lugs themselves might be built up in pieces secured together in any convenient manner, so that the same ring could accommodate a number of different cylinders.

The thread-carrier O' is mounted upon a 95 vertical strip, L, pivoted to the outside of the cam-cylinder E at l, and said strip is provided with a transverse slot, p', through which the stud p projects, said stud having a shoulder, as shown in Fig. 3, so that when the strip L 100 is sprung outward it may be turned radially upon its pivot l until the edge of the slot is

thrown over the shoulder of the stud *p*, thus holding it outward, so that the thread-carrier no longer brings thread within the reach of the needles, and the cylinder may be raised. 5 A spring, *p'*, surrounds the stud *l* and bears upon the standard *L*.

The needle-cylinder *F* is of the usual form; but the needles *b* are bent laterally at their lower ends, as indicated at *b'*, Fig. 6, so that 10 they are held firmly in the vertical slots of the needle-cylinder by means of the spring thus formed.

This method of construction enables me to substitute for the usual spring-band which surrounds the needle-cylinder and needles a solid ring, *d*, which is secured in a circumferential groove, *v*, extending entirely around the outside of the needle-cylinder *F*. The ring *d* is constructed in segments, as indicated at Figs. 15 2c 4 and 5, so that it can be applied around and within the groove *v*, the ends of the segments being united by screws *w* and splicing-pieces *u*.

The use of a solid ring held positively in 25 position around the needle-cylinder and of the spring-shank *b'* upon each individual needle renders the needles perfectly steady, though free to move vertically, so that no matter at what speed the machine may be run there is no danger of the needles jumping upward nor 30 outward. This system of a positive support is further carried out by the use of the split ring *G*, which holds the needle-cylinder, and whose use prevents the cylinder from shifting its position bodily while running.

35 The remaining feature of construction, which combines with those just described to render the action of the needles positive and certain irrespective of the speed at which they may be run, is the use of stationary driving-cams 40 for the needles *b*. These cams are represented by *J K N e n*, and are all fixed, the movable cam *f* having nothing to do with the operation of the needles in the act of knitting, but being for another purpose, which will be hereinafter 45 explained.

As will be seen by reference to Fig. 1, the operative cam-surfaces are made right and left, so that the machine can be turned backward and forward by means of the winch *W*, to knit 50 heels, &c., in the well-known manner, and since there is nothing left to the uncertain action of springs or gravity in the operation of said cams, (as is the case where movable cams are used upon the cam-cylinder,) the speed of the 55 machine may be increased to a very high point. It is this feature of positive action and firm support of the needles which enables me to obtain the advantages I have before referred to.

In order to throw any desired needles out of 60 play, so as to form ribbed work, I provide around the bottom of the cam-cylinder *E* an interior groove, *r*, of a depth sufficient to receive the projecting hub *c* of the needles. The cam-surfaces *e n*, it will be observed, run down 65 into said grooves *r*, and the movable cam-piece *f* can be turned (by means of its shaft *f'*, which

projects out through the cam-cylinder) into the position indicated by the solid lines in Fig. 1. When it is in this position, if a needle be depressed by the operator until its hub *c* engages beneath the cam *f*, the rotation of the cam-cylinder *E* will cause said needle to descend until its hub gets entirely within the groove *r*, where it will be held and prevented from rising during the operation of the machine. This action will of course draw down the hook of the needle so low as to prevent its engaging with the thread, and as any desired number of needles may be thus thrown down and held during any length of time ribbed work may be formed. 70 75 80

By turning the cam *f* into the position indicated by the dotted lines in Fig. 1, it will be seen that its point now enters beneath the bottom of the groove *r*, so that when, by the rotation of the cam-cylinder *E*, the hub *c* of a needle reaches the upper surface of the cam *f*, the hub *c* will rise upon the incline of said cam until it is thrown clear of the groove *r*, and will be in a position to engage with the operative cam-surfaces, as before. Thus, by turning the movable cam *f* downward, the needles which have been thrown out of play may be again brought into play by the rotation of the cam-cylinder *E* itself, and without the necessity of the operator picking up each individual needle. Moreover, this depression of the needles which are to be thrown out of play (instead of picking them up by hand and throwing them outward, as has heretofore been practiced) I deem a feature of value, since it prevents the non-operative needles from getting entangled with the threads and from being in the way of the operator. 90 95 100

I am aware that it is not new to support the needle-cylinder in a split ring which can be raised or lowered by turning it upon inclined surfaces, and I am also aware that it is not new to use a bracket for supporting the needle-cylinder, nor to surround the needles with a non-elastic band composed of two rings with cut-away portions which can be turned so as to coincide; hence I do not claim any of said methods of construction, broadly, but only the particular combinations hereinafter set forth as follows: 105 110 115

Having thus described my invention, I claim in a rotary knitting-machine the following combinations:

1. The combination, with the needle-cylinder, of the split ring *G*, having a clamping-screw, *j*, the bracket *H*, the shaft *R*, having a screw-thread upon its upper end, the frame having a sleeve in which said shaft slides freely, the nut engaging with said screw-thread and carrying a stop-pin, and the index-plate having openings with which said stop-pin engages, substantially as set forth. 120 125

2. The combination, with the shaft *R*, cylinder *F*, bracket *H*, split ring *G*, clamping-screw *j*, and the nut *h*, engaging with said shaft and provided with a stop-pin, of an index-plate 130

having holes with which said stop-pin engages and provided with movable pins *m*, adapted to be inserted in said holes to limit the range of motion of the stop-pin, substantially as set forth.

3. The combination, with the cam-cylinder having the lower driving-cams, *e n*, and the groove *r*, into which the lower driving-cams, *e n*, lead, of the pivoted wedge-shaped cam *f*, whose lower surface extends, when said cam *f* is turned up, from a point within the range of the cams *e n* down into the groove *r*, and whose upper surface extends, when said cam *f* is

turned down, from the bottom of the groove *r* to a point within the range of the cams *e n*, substantially as set forth. 15

4. The combination, with the thread-carrier having a transverse slot therein, of a shouldered stud projecting through said slot and a spring bearing against the thread-carrier, substantially as set forth. 20
